Inventor:

R. M. Seldis

United States Patent Office.

R. M. SELDIS, OF NEW YORK, N. Y.

Design No. 2,841, dated November 26, 1867.

DESIGN FOR A MUFF.

The Schedule referred to in these Letters Patent and making part of the same.

ALL WHOM IT MAY CONCERN:

Be it known that I, R. M. SELDIS, of New York, in the county and State of New York, have invented a and original Design for Muff; and I do hereby declare that the following is a full, clear, and exact description thereof, which will enable others skilled in the art to understand the same, reference being had to the accompanying drawing, forming part of this specification.

The drawing represents a perspective view of my invention.

This invention relates to a new design for a pouch-attachment to muffs, and consists in suspending a fur-ered pouch, A, from the under side of a muff, B, so that the height of the muff will be increased, as shown. Cover C to the pouch A is covered with fur, as shown, and the edges of the pouch, at the ends and bottom the same, are ornamented with fine hair fringes D, as shown. Tasselled cords E E, are, as usual, suspended n the ends of the muff, and a tasselled cord, F, serves as a handle for suspending it and the pouch.

What I claim as my invention, and desire to secure by Letters Patent, is—

The design or pattern for muffs, herein set forth and shown.

R. M. SELDIS.
